SEWING MACHINE

Albert H. Weis, Nyack, N. Y., assignor to Wilcox & Gibbs Sewing Machine Company, New York, N. Y., a corporation of New York

Application December 4, 1940, Serial No. 368,423

9 Claims. (Cl. 112—200)

This invention relates to sewing machines and particularly to looper mechanisms and their driving connections as used in sewing machines.

It is an object of the invention to provide a sewing machine in which access to the looper, or loopers, for the purpose of threading, replacement and inspection may be facilitated.

It is another object of the invention to provide means of a simple and effective nature through and by which the immediately foregoing object may be accomplished.

A feature of the invention, resulting in the attainment of the foregoing objects, resides in the provision of a sewing machine including a connecting rod or driving member for rocking a looper carrier member and its associated looper and in which a particularly effective means is provided for readily connecting the driving member and looper carrier member and also for disconnecting the driving member and looper carrier member to enable movement of these members to positions where ready access may be had thereto.

Another and related feature of the invention resides in the provision of a sewing machine in which ready access may be had not only to a looper carrier member and associated looper but also to a looper thread member carried by and movable with the connecting member by which the looper carrier member is rocked.

Another feature of the invention resides in the very effective, positive and automatically acting means by which a driving component may be securely connected to and wholly disconnected from an operating component of a sewing machine.

Other objects, features and advantages will hereinafter appear.

In the drawings:

Figure 1 is a front view of a sewing machine embodying the present invention, the frame of the sewing machine being shown in dotted lines and in section to facilitate the disclosure of those elements incorporating the novel features of the invention.

Fig. 2 is a perspective view illustrating the novel association and connection of the looper carrier and looper which together constitute an operating component of the sewing machine, and the connecting rod which constitutes a driving component of the sewing machine.

Fig. 3 is an end view of the connecting elements between the looper carrier and connecting rod, shown in Fig. 4.

Fig. 4 is an enlarged detail view showing the organization of elements whereby the looper carrier and connecting rod may be so readily connected and disconnected.

Fig. 5 is a sectional view taken on the line 5—5 of Fig. 4.

Fig. 6 is a detail view of the snap-acting retaining element.

Before describing the present improvements and mode of operation thereof in detail it should be understood that the invention is not limited to the details of construction and arrangement of parts shown in the accompanying drawings, which are merely illustrative of the present preferred embodiments, since the invention is capable of other embodiments, and the phraseology employed is for the purpose of description and not of limitation.

Referring more particularly to the drawings there is shown for the purpose of illustrating an advantageous embodiment of the present invention, a sewing machine which in general organization is substantially identical with the sewing machine shown in my prior Patent No. 1,906,294, granted May 2, 1933.

This sewing machine includes a base or lower arm 11 from which extends a hollow trunk 12 serving as a support for an overhanging arm 13 terminating in a head 14 mounting, in a usual manner, a needle bar 15 and needle 16 and also a presser bar, not shown, and presser foot 17 which cooperates with a throat plate 18 and feed dog 19 for advancing the work.

A pulley or belt wheel 20 carried by a crank shaft 21 mounted in bearings 22 and 23 on the base 11, serves as a means for transmitting rotary movement directly to the crank shaft 21 and, through the connecting rods 24, to a crank shaft 25 supported by bearings 26 and 27 in the overhanging arm and operatively connected by the needle reciprocating mechanism 28 to the needle bar 15.

Connected to the crank shaft 21 by a coupling 29 is a main drive shaft 30 extending longitudinally of the lower arm 11 and supported in a bearing 31 provided in a standard 32 which together with a bracket 33 and an apron 34 on the trunk 12 supports a cloth or work plate 35. A suitable feed lifting eccentric 36 on the shaft 30 may be provided for raising and lowering the feed dog 19 and its carrier 37 in a usual manner. Likewise, suitable and usual means, not shown, may be provided for effecting back and forth movements of the feed dog carrier and the feed dog supported thereby.

Also, operated through connections with the main shaft 30 is a looper carrier 38, supporting as an element separate or integral therewith a looper 39 and mounted for rocking movement on a pair of conical screws 40 which engage a bearing portion 41 of the looper carrier and which are screwed into lugs 42 and 43 of a dovetail slide member 44 guided for reciprocating motion transverse the main drive shaft by a pair of gibbs 45 on the base of the sewing machine. Reciprocation of the slide 44 and, therefore, lateral

movement of the looper carrier 38 and looper 39 may be effected by an eccentric, not shown, mounted on the main drive shaft 30 and co-operable with the bearing 46 provided by a split block 47 located between jaws 48 and 49 on the slide.

Rocking movement of the looper carrier 38 and looper 39 may be effected by a connecting rod 50, secured at one end 51 to the looper carrier 38 and provided at the other end with a ball socket 52 operating on a ball stud 53 carried by one arm 54 of a two-arm lever 55 secured by a screw 56 to a stud 57 which operates in bearings 58 and 59 carried by a supporting bracket 60 secured to the machine base by screws 61. The other arm 62 of the lever 55 is also provided with a ball stud 63 secured thereto by a screw 64. A ball socket 65, confining the ball stud 63 and connected to one end of a rod 66 the other end of which is connected to an eccentric strap 67 operable from the main drive shaft, serves to transmit the motion of the rod 66 to oscillate the lever 55 and through the connecting rod 50 to rock the looper carrier 38 and looper 39 into and out of the needle loop.

The details of the construction and operation of the means briefly described above for effecting rocking and lateral movements of the looper carrier and looper are fully illustrated and described in my prior Patent No. 1,906,294 and in and of themselves form no part of the present invention.

However, and of importance, the present invention provides an especially advantageous means 68 whereby the connecting rod 50 may be wholly and readily disconnected from the looper carrier 38 to permit the latter and particularly its looper 39 to be moved to a position facilitating the threading thereof and to permit a movement of the connecting rod 50 to give greater freedom to an operator's fingers in threading the looper and its thread leading eyelet member 69 and also in threading a looper thread member 70 which may be advantageously mounted on the connecting rod 50 for reciprocating movement therewith in predetermined relation with the rocking movement of the looper 39.

The disconnecting, and also connecting, means 68 includes, as shown most clearly in Figs. 3, 4, 5 and 6, a special stud 71 having a threaded end portion 72 adapted to be screwed into the looper carrier 38. In addition, this stud 71 has a bearing portion 73, adapted to be associated with a ball and socket assembly 74 secured to the end 51 of the connecting rod 50, and which extends outwardly from a shoulder 75 to terminate in a round ended substantially conical tip 76.

The ball and socket assembly 74 comprises a ball socket member 77, one section 78 of which may be formed in the usual manner with a portion 79 for receiving the threaded end 51 of the connecting rod 50, and the other or cap section 80 of which may be secured to the section 78 by screws 81 in a well-known and conventional manner. Of importance, however, a ball-like member 82 confined in the socket 77 defined by the sections 78 and 80 is not immovably fixed on a stud secured to the looper carrier, but is formed with a central aperture or bore 84 therethrough adapted to receive the bearing portion 73 of the special stud. Preferably a bevelled edge 85 is formed to define the entrance to the side of the socket facing the shoulder 75 on the stud 71.

To maintain the stud 71 and ball and socket assembly 74 thus associated there is provided an

advantageous snap-acting means in the form of substantially U-shaped resilient member 86 having two fingers 87 adapted to snap into a groove 88 intermediate the bearing portion 73 and tip 76 of the stud 71, and having a portion 89 bent at an angle to the fingers 87 adapted to fit over the threaded end 51 of the connecting rod 50 and be held in position against the ball socket member 77 by a lock or holding nut 90 which also holds in position the looper thread member 70. With this construction, it will be readily appreciated, the ball and socket assembly 74 is releasably maintained on the stud 71 between the shoulder 75 and the groove 88.

In operatively connecting the connecting rod 50 and looper carrier 38, and assuming that these elements are disassociated, one from the other, the apertured ball-like member 82 in the ball and socket assembly 74 on one end 51 of the connecting rod 50 is aligned with the stud 71 on the looper carrier. Then, upon moving the connecting rod 50 laterally toward the stud 71, the tip 76 of the latter element is caused to enter the aperture or bore 84 in the ball-like member 82. When the ball and socket assembly 74 is fully and properly mounted on the bearing portion 73 of the stud 71, the two spring fingers 87 of the snap-acting member 86 which is aligned with the apertured ball-like member 82, automatically snap into the detent groove 88 and thus locks the ball and socket assembly 74 against adverse and disassociating sliding movement longitudinally of the stud 71.

When it is desired to disconnect the connecting rod 50 and looper carrier 38 it merely is necessary to grasp the connecting rod or ball and socket assembly and pull the same laterally away from the looper carrier. This pull causes the spring fingers 87 automatically to slide up and out of the detent groove 88, whereupon the complete disassociation of looper carrier and connecting rod is a simple matter.

Accordingly, with the present invention it is seen that while in an associated relation the looper carrier and connecting rod may be effectively connected through a ball and socket assembly 74 which permits universal or substantially universal movement between the elements, they are also adapted to be wholly disconnected to permit advantageous independent movement of the looper carrier 38 and looper 39, and the connecting rod 50.

This independent movement of the looper carrier and looper, made possible by the novel utilization of the connecting and disconnecting means 68, enables the looper to be swung to a retracted position, not possible while the looper carrier is connected to the connecting rod, where ready access for threading may be had either through the front of the lower arm or through a special opening 91 which, if desired, may be provided in the cloth plate 85 and closed by a removable closure plate 92. Moreover, by moving the connecting rod away from the looper, greater freedom of movement is afforded the fingers or hands of an operator in threading the looper 39 and its thread leading eyelet member 69 as well as the looper thread member 70 carried by the connecting rod 50. As in the case of the looper 39, the looper thread member 70 may be readily threaded either through the front of the lower arm or through the opening 91 in the cloth plate. When the connecting rod 50 is swung upwardly to move the thread member into

the opening 91, the latter member may be threaded above the work plate.

Variations and modifications may be made within the scope of this invention and portions of the improvements may be used without others.

Having thus described the invention, what is claimed as new is:

1. In a sewing machine having a looper carrier member with a looper and mounted for rocking movement, the combination of a connecting rod member for rocking said looper carrier member and looper; a ball and socket means carried by one of said members; connecting means on the other of said members, slideable relative to and in and out of operative association with said ball and socket means; and yielding means carried by said one of said members and movable therewith and with said ball and socket means relative to said connecting means for releasably locking said connecting means and said ball and socket means in operative association.

2. In a sewing machine having a driving component and an operating component, the combination of a ball socket member on one of said components; an apertured ball element confined in said socket member; a connecting element on the other of said components, slideable relative to and in and out of operative association with said apertured ball element; and resilient detent means supported with one of said elements for relative movement therewith with respect to the other of said elements when the elements are slid into operative association with respect to each other, for arresting relative longitudinal sliding movement of said connecting element and said apertured ball element when said elements are in said operative association.

3. In a sewing machine having a looper carrier element mounted for rocking movement and a connecting rod element for rocking said looper carrier element, the combination of a ball socket member carried by one of said elements; an apertured ball member confined in said socket member; connecting means on the other of said elements, having a groove therein and slideable longitudinally relative to and in and out of operative association with said apertured ball member; and detent means supported and movable with said ball socket member, engageable in said groove for arresting relative longitudinal sliding movement between said connecting means and said ball socket and apertured ball members.

4. In a sewing machine having a looper carrier mounted for rocking movement and a connecting rod member for rocking said looper carrier, the combination of a ball socket member having an apertured ball member confined therein, carried by said connecting rod member; a connecting stud carried by said looper carrier, having a groove therein, extending into and slideable longitudinally relative to said apertured ball member; and a spring finger carried by said connecting rod member for snapping into said groove and arresting relative longitudinal sliding movement between said connecting stud and said ball socket member.

5. In a sewing machine having a looper carrier mounted for rocking movement and a connecting rod member for rocking said looper carrier, the combination of a ball socket member confining an apertured ball member therein, carried by said connecting rod member; a connecting stud

having a groove therein, carried by said looper carrier and extending through and slideable longitudinally relative to said apertured ball member; and a retaining member engageable in said groove for maintaining said ball socket member and said connecting stud in operative association.

6. In a sewing machine having a looper carrier mounted for rocking movement and a connecting rod member for rocking said looper carrier, the combination of a ball socket member confining an apertured ball member therein, carried by said connecting rod member; a connecting stud having a groove therein carried by said looper carrier and extending through and slideable longitudinally relative to said apertured ball member; and a retaining member having laterally spaced yielding fingers, carried by said connecting rod member and aligned with said apertured ball member, for snapping into said groove and maintaining said ball socket member and said connecting stud in operative association.

7. In a sewing machine having a looper carrier element mounted for rocking movement and a connecting rod element for rocking said looper carrier element, the combination of a ball socket member confining an apertured ball member therein, carried by one of said elements; a connecting means on the other of said elements, slideable longitudinally relative to and into and out of said apertured ball member; and snap-acting means, movable with said ball socket member and aligned with said apertured ball member for automatically locking said apertured ball member on said connecting member when the latter members are slid into operative association with respect to each other.

8. In a sewing machine having a looper carrier element mounted for rocking movement and a connecting rod element for rocking said looper carrier element, the combination of a ball socket member carried by one of said elements; an apertured ball member confined in said socket member; connecting means on the other of said elements, having a groove therein and slideable longitudinally relative to and in and out of operative association with said apertured ball member; a looper thread member mounted on and movable with said connecting rod element; and detent means supported by and movable with said ball socket member, engageable in said groove for arresting relative longitudinal sliding movement between said connecting means and said ball socket and apertured ball members.

9. In a sewing machine having a looper carrier element mounted for rocking movement and a connecting rod element for rocking said looper carrier element, the combination of a ball socket means confining an apertured ball member therein, carried by one of said elements; a connecting stud member carried by the other of said elements and extending through and slideable longitudinally relative to said apertured ball member, one of said members having a detent-receiving means associated therewith; and a resilient detent supported and movable with the other of said members relative to said member having a detent-receiving means, engageable in said detent-receiving means when said members are slid longitudinally relative to each other, for maintaining said members in operative association.
